UNITED STATES PATENT OFFICE.

NEWTON S. CHAPMAN, OF KANSAS CITY, MISSOURI, ASSIGNOR OF ONE-HALF
TO FRANK HAGEMAN, OF SAME PLACE.

ELECTRIC RAILROAD-SIGNAL ALARM.

SPECIFICATION forming part of Letters Patent No. 453,578, dated June 2, 1891.

Application filed February 18, 1891. Serial No. 381,826. (No model.)

To all whom it may concern:

Be it known that I, NEWTON S. CHAPMAN, a citizen of the United States, residing at Kansas City, in the county of Jackson and State of Missouri, have invented certain new and useful Improvements in Electric Railroad-Signal Alarms, of which the following is a full, clear, and exact description, reference being had to the accompanying drawings, forming a part hereof.

My invention relates to improvements in electrical railroad-signal alarms, its objects being, first, to provide a means whereby an alarm may be given when two trains are going in opposite directions on the same track; second, to notify the engineer of an open switch; third, to provide a means whereby the engineer may test the batteries, &c., on his engine by dropping a set of brushes on the circuit-wire, thereby forming a circuit; fourth, to provide a metallic brush which will adjust itself to the circuit-wires, thereby overcoming the wear and tear necessarily caused by the rocking of the engine. These ends I attain by employing the mechanism and devices illustrated in the accompanying drawings, in which—

Figure I is a side elevation of an engine having my invention applied thereto. Fig. II is a detail perspective of the metallic circuit-brushes, cleaning-brush, and plow secured to a frame or plate. Fig. III is a side view of same attached to the heel of the pilot. Fig. IV is a detail in perspective of the testing-brushes, showing the levers by which they are operated. Fig. V represents a portion of the cab, showing the location of the signal-alarm bell. Fig. VI is a plan view of a railroad-track, showing the manner in which my invention may be applied to crossings, switches, side tracks, &c., and Fig. VII is a detail in perspective of the spool, around which the circuit-wire is secured.

Referring to the drawings by letter, A represents a locomotive engine and cab of the ordinary construction, which is provided with a pilot B. To the heels of said pilot are properly secured plates or frames C, which are braced thereto by means of the brace-rods E. Rigidly secured to said plates C are plows

accumulate from the circuit-wires. Directly behind these plows are brushes G, made of any suitable material, which are non-conductors of electricity. These brushes remove all the remaining snow and ice from the circuit-wires, leaving them free to contact with the metallic brushes D. Said brushes D are rigidly secured to the segmental rods d, which have their foremost ends secured to the lugs c' by suitable bolts. The opposite ends of the segmental bars d are perforated and fit loosely over pins f, and are made adjustable by means of the coil-springs F. Said pins f are rigidly secured to the lugs f'.

E' are plows similar to the ones heretofore described, but operating in the reverse direction, so as to clear the circuit-line from obstructions when the locomotive is being run backward.

H is the wire which conducts the electrical current from the battery a to the brushes D, and from thence to the circuit-wires N.

I are plates secured to a horizontal bar i, to which are secured the testing-brushes I', said testing-brushes being constructed substantially as those heretofore described.

K are swinging braces, which are secured to the yoke of the engine, by which the testing-brushing I' are suspended. Said brushes I' are secured to the plates I in a manner similar to those already described, and the bar i, which connects the brushes, is hinged at its center to a suspending lever J, whose upper end is fulcrumed to a triangular arm j, which in turn is fulcrumed to a lever J', this being operated by hand-lever J''.

These levers, brushes, &c., provide a means whereby the batteries may be tested at any time and while the train is in motion, this being done by throwing lever J'', thereby bringing brushes I' in contact with circuit-line which completes the electrical circuit.

L represents the alarm-bell, which may be located at any convenient place in the cab. Said bell is sounded by the armature l being attracted by the magnets, thereby bringing the hammer against the same, as in ordinary cases. H represents a telephone, which may be provided with my invention, if desired.

N are the circuit-wires of the main track, which convey the electrical current from one engine to another on the same track, said

wires being secured along the side of the rails by means of the non-conducting spools O, which are secured to the ties by suitable spikes o, these being placed at suitable intervals along the track.

P is a switch-lever, operated by hand-lever p, by means of which the switch may be brought in coincidence with the side tracks S' and S''. Suitably secured to the switch-lever P is a bar Q, which is fulcrumed at its opposite end. This bar is provided with a copper plate q, which is properly secured thereto. This contacts with the contact points r and r' when the switch is open, thereby allowing the current to pass from circuit-wire N through contact q to contact r or r', as the case may be, and back along the wire n to the circuit-wire N, and through this wire it is carried back to the batteries, energizing the magnet and sounding the alarm.

The metallic brushes D are insulated from the plate or frame C and the segmental bars d, so that none of the current is wasted. The contact-point q on the arm Q is also insulated from said arm for the same purpose. It is obvious that the circuit-wire may be carried along the entire length of the track or located at intervals or at dangerous places, such as curves, switches, side tracks, crossings, &c.

The operation of the invention is as follows: The metallic brushes being in contact with the circuit-wires at the sides of the track, it is evident that as soon as two trains pass

upon the same section of circuit-wires a circuit is formed between the two engines, the current passing to the brushes through the conducting-wires H, then to the circuit-wires at the sides of the rails, and when the circuit is completed the armatures which operate the bells on both engines are attracted by the magnets, thus notifying both engineers at the same instant that a train is approaching from an opposite direction on the same track, or of an open switch.

Having thus fully described my invention, what I claim as being new, and desire to secure by Letters Patent, is—

1. In an electric railroad-signal alarm, the combination of a series of locomotive-engines, each provided with an electric generator, alarm, insulated metallic brushes, and testing-brushes suspended from the yoke of the engine, which are operated by suitable arms and levers, for the purposes and substantially as set forth and described.

2. In an electric signal-alarm for railroads, the testing-brushes I', hung on suitable plates and bars, suspended and operated by rods and levers, substantially as and for the purposes set forth and described.

In testimony whereof I affix my signature in presence of two witnesses.

NEWTON S. CHAPMAN.
